CARD FILE

Hildaur L. Neilsen, 2 W. Maple St., Metuchen, N.J.

Filed Jan. 2, 1959, Ser. No. 54,030

Term of patent 14 years

(Cl. D74—2)

The figure on the drawing is a perspective view of a card file showing my new design, the opposite sides thereto being similar in appearance.

I claim:

The ornamental design for a card file, as shown and described.
